UNITED STATES PATENT OFFICE.

SIDNEY THOMAS, OF HAMPSTEAD, LONDON, ENGLAND.

FORMING OR PROFILE TEMPLATE.

Application filed November 14, 1925, Serial No. 69,057, and in Great Britain October 6, 1925.

This invention relates to forming or profile templates and refers more particularly to that type of template which comprises a number of metal strips or the like mounted in a clamp or holder and capable of being slid or moved and set to a desired shape as for example when placed and pressed into contact with an article to produce a representation of the profile or shape of the article.

With such templates difficulty is experienced sometimes in obtaining an accurate profile of an article due to the fact that there is a tendency to press the metal strips unevenly against the article whose profile or shape it is desired to obtain.

Now the main object of the present invention is to provide an improved template by means of which an accurate profile of an article can be obtained.

With this end in view and such others as may hereinafter appear or are incidental thereto the invention may be said to comprise a forming or profile template having a number of metal strips or the like mounted in a clamp provided with means whereby said clamp and strips can be moved on a supporting member in such manner that the strips can be pressed evenly against the article the profile or shape of which it is desired to obtain said supporting member being if desired provided with means for engaging said article.

In a preferred embodiment of the invention the improved template comprises a number of strips, needles, or the like of metal or other suitable material located between guide pieces and slidably mounted within a clamp comprising an upper and lower member adjustably and resiliently secured together by means of thumb screws or the like.

For the purpose of pressing the metal strips evenly against an article the profile or shape of which it is desired to obtain the said clamp is conveniently mounted on a supporting member preferably of bow or U shape the legs of which are formed as or provided with racks which are engaged by pinions or gear wheels mounted on the clamp between the upper and lower members and capable of being rotated by means of thumb nuts.

The supporting member is preferably provided with adjusting screws which can be caused to engage the article the profile or

shape of which is being obtained and if desired a spirit level may be mounted on the upper member of the clamp.

In order that the invention may be clearly understood reference will now be made to the accompanying drawings wherein a preferred embodiment has been illustrated by way of example.

Fig. 1 illustrates a plan view of the improved template and

Fig. 2 is a sectional view on the line 2—2 of Fig. 1.

Referring to the drawings wherein the same reference numerals indicate the same or similar parts the improved template comprises a clamp 1 formed of an upper member 2 and a lower member 3 the said members being resiliently secured together by thumb screws 4 and springs 5.

Located between the members 2 and 3 of the clamp are a number of strips, needles, or the like 6 of metal or other suitable material the said strips 6 being slidably mounted between guide pieces 7 having backing strips 8 in contact therewith.

For the purpose of pressing the strips 6 evenly against an article the profile or shape of which it is desired to obtain the said clamp 1 is mounted conveniently on a supporting member 9 of bow or U shape the legs 10 and 11 of which are provided with racks 12 and 13 with which pinions 14 and 15 engage the said pinions being located between the members 2 and 3 of the clamp 1 and secured to short spindles 16 and 17 which can be rotated by thumb nuts 18 and 19 also secured to said spindles where clamp 1 and strips 6 can be moved in either direction on said supporting member.

The supporting member 9 may be provided if desired with adjusting screws 20 and 21 mounted in bosses 22 and 23 on the legs 10 and 11 respectively the said screws being caused to engage the article the profile or shape of which is being obtained thereby securing the supporting member 9 in position.

A spirit level may if desired be mounted on the upper member 2 of the clamp 1.

The improved template is particularly adapted for taking the profile or shape of the flanges on the tyres of the wheels of railway and tramway vehicles and also for taking the profiles or shapes of sections of the rails but can be used for taking other profiles.

When it is desired to take the profile or shape of a flange on a wheel of a railway vehicle for example the adjusting screws 20 and 21 are brought into engagement with the wheel preferably with recesses previously formed on the wheel centre of the wheel after which the thumb nuts 18 and 19 controlling the pinions 14 and 15 are operated and the strips 6 pressed on to the surface of the tyre. The template is then removed and placed on a card or the like and a sketch made of the profile.

The racks 12 and 13 may be formed directly on the legs 10 and 11 or may be formed on separate strips secured to the legs 10 and 11 as by screws or the like.

What I claim and desire to secure by Letters Patent of the United States is:—

1. A forming or profile template comprising a clamp, a number of strips mounted in said clamp so as to be capable of being moved thereon, a supporting member for the clamp, there being toothed portions on said supporting member, toothed members on said clamp engaging said toothed portions, and means for operating said toothed members whereby the clamp will be moved on the supporting member.

2. A forming or profile template comprising a clamp composed of an upper member and a lower member, means for securing resiliently said members together, guide pieces located between said members, movable

strips located between said guide pieces, a supporting member for said clamp, there being rack portions on said supporting member, pinions on the clamp engaging said rack portions and means whereby said pinions can be rotated.

3. A forming or profile template comprising a clamp composed of an upper member and a lower member, means for resiliently securing said members together, guide pieces located between said members, movable strips located between said guide pieces, a supporting member for said clamp, there being rack portions on said member, spindles on said clamp, pinions secured to said spindles between the upper and lower members of the clamp, and thumb-nuts secured to said spindles.

4. A forming or profile template comprising a clamp, strips mounted in said clamp so as to be capable of being moved thereon, a bow-shaped supporting member for the clamp, racks on said supporting member, pinions on said clamp, means for operating said pinions whereby said clamp and strips can be moved on the supporting member, and adjusting screws on said supporting member for engaging the article the profile of which it is desired to obtain.

In testimony whereof I have signed my name to this specification.

SIDNEY THOMAS.
